PORTABLE PIER

Ivan J. Wanless, Chevy Chase, Md., assignor of
one-fifth to Sol B. Wiczer, Washington, D. C.

Application November 5, 1947, Serial No. 784,255

8 Claims. (Cl. 61—48)

1

The present invention relates to a portable pier or wharf and in particular to a pier for inland waters wherein the pier is desirably knocked down and stored in portable sections during extended periods when not in use or such as when waters are frozen.

It is accordingly a primary object of the present invention to design a pier of easily assemblable parts.

It is a further object to design the pier such that only the superstructure need be removed with relatively permanently installed foot blocks for mounting the pier thereon.

It is a further object to design the pier elements of light and strong materials and of sufficient versatility that considerable variation of the shape and size of the pier is possible.

The construction is best understood by reference to the drawings wherein an illustrative example of the construction according to the present invention is shown.

Figure 1 is a profile of the pier in place.

Figure 2 is a plan view showing a suitable arrangement of deck boards.

Figure 3 is a detail showing the mounting of a deck board and side channel in the end of a leg post.

Figure 4 is a detail of a leg post as mounted on a foot block and carrying a side channel with a deck board removed but shown in detail above in position for mounting in the side channel.

Figure 5 is a detailed view of a foot block.

Figure 6 is a detailed view of a deck board.

Figure 7 is a detail of a modified construction of a leg post used for side extension of the pier.

As shown in Figure 1, the pier generally comprises permanently set foot blocks 10 supporting removable leg posts 11 which in turn support side channels 12 on which are mounted deck boards 13.

The foot blocks 10 as shown may be of cast, extruded, or rolled and welded tubular metal for lightness of construction, but may be solid if desired. They are pointed or tapered at 14 to facilitate driving into the mud 15 at the bottom of the water 16 at regularly spaced intervals extending from the shore bank 17. At a short distance from the top of the block 10, collar 18 is fastened as by welding which supports the foot block at the under water ground surface in stable position preventing further sinking into the mud, the upper end 19 of the block 10 protrudes a short distance above the collar 18 and comprises a neck upon which the hollow leg posts 11 are removably but stably supported as shown

2

at 20 in Figure 4. Thus as shown each leg post 11 surrounds the neck 19 and fits closely enough to be prevented from deviating substantially from the vertical and is further supported by the collar 18.

The upper end of each leg post 11 is cut away with slots or grooves at 21 to receive and support a portion of a side channel 12.

The side channels 12 are thus supported in parallel arrangement a sufficient distance apart to receive and support the deck boards 13. The deck boards are generally constructed of thin sheet or expanded metal. Where sheet metal is used the surface is perforated as shown at 22 or otherwise roughened as by knurling, corrugating or coating with a roughening substance to give a safe non-skid tread or walking surface.

The edges of the deck boards 13 are turned down to form flanges 23 serving to strengthen the boards and provide mating elements for support in the side channels 12 as shown in Figures 3 and 4.

The side channels 12 and deck boards 13 are bored at 24 through the sides and flanges to receive quick fastening pins or bolts 25. The leg posts 11 are also bored at 24 to receive a pin 25 so that the side channels 12, deck boards 13 and leg posts 11 are all quickly pinned together by pins 25 in a quick fastening and unfastening but sturdy arrangement as shown in detail in Figure 3.

It may be desirable to extend the pier in a direction parallel to the bank 17. For example, the pier may be made extensible from both leg posts A—A' shown in Figure 2 in a side construction. For such construction a modified type of leg post 11 would be used at A—A' as shown in detail in Figure 7. For this purpose extra grooves are cut in the top of the leg posts A—A' at 26 to support two side channels 12, one of which is at right angles to the other, thus providing support for other channels mounted angularly and enabling a portion of the pier to be extended sideways parallel to the bank or in other directions as desired.

As thus described a pier may be quickly assembled of small structural elements mounted on permanent foot blocks merely by putting the parts together and temporarily fastening with pins or bolts. The foot blocks when installed are set apart the desired distance and new foot blocks are added when the pier is extended in any direction.

For purposes of easy handling of light and for non-corrosive construction, aluminum alloy with non-corrosive characteristics is preferred, but

other materials of non-corrosive nature may be used. The pier may be painted but the use of non-corrosive material does not require this maintenance.

Certain modifications will occur to those skilled in the art and it is intended that the specification be interpreted as broadly as defined in the claims.

I claim:

1. A knock down pier having open channel members comprising side supports mounted on spaced piles, each of said channel members having a correspondingly narrow channel and adapted to be mounted with the channel thereof invertedly open to receive and matingly support therein the flanged end of a plurality of deck boards, a plurality of deck boards having downturned flanged ends removably received in said open side channels, whereby the mated channels and deck boards form a strongly braced pier deck, the openings of said channel members being sized to matingly fit the flanged ends of said deck boards, and means for removably fastening said deck boards in said side channels.

2. A knock down pier comprising leg posts detachably resting on foot blocks, said leg posts being radially slotted at the upper ends to receive and support removably fastened channel members, channel members comprising side supports mounted in said slots, and a plurality of deck boards having downturned flanges removably received in said side channels.

3. A knock down pier having a plurality of spaced permanently embedded foot blocks, a leg post supported vertically and removably mounted on each foot block, radial slots in the upper ends of the leg posts, open U-shaped side channels detachably fastened in said leg post slots and a plurality of deck boards having downturned flanges removably received in said side channels.

4. A knock down pier having a plurality of spaced leg posts detachably resting on foot blocks, said leg posts being radially slotted at the upper ends to receive and support removably fastened upwardly open channel members comprising side supports, a plurality of deck boards having downturned flanges removably received in said open side channels, at least two of said leg posts having a plurality of radial slots angularly disposed to each other whereby a plurality of side members may be mounted on a single leg post whereby to extend the pier in angular directions.

5. In a portable knock-down pier construction the combination of open channel members mounted to receive and support deck boards matingly fitted in the channel thereof each deck board comprising a sheet metal member having the perimeter bounded by four flanges all turned down in the same direction, the parallel flanges upon two opposite sides being deep enough to impart rigidity to the deck board surface, the other two opposite flanges being deeper to be matingly fitted and supported in the open side of said channel members.

6. In a portable knock-down pier construction, the combination of foot blocks each supporting a tubular pier leg, each foot block adapted to be permanently embedded in the bottom of a body of water defining a pier site, said foot block comprising a tubular pile member of relatively short length, pointed at one end, and adapted to be driven into the ground and having permanently mounted intermediate the ends a collar adapted to lie upon the water bottom and prevent the pile member from sinking, said collar being positioned at a portion intermediate the top and bottom of said pile to allow a portion of the tubular member to extend above the ground a short distance sufficient to matingly receive and support a tubular leg member for a temporary demountable support thereof, and each of said tubular legs being notched at the upper end to matingly receive and support side bracing members of the pier.

7. A portable knock-down pier comprising intermediately flanged foot blocks adapted to be permanently embedded at the pier site, comprising a short pile element extending above the ground level to matingly receive and vertically support tubular pier legs, a removable tubular pier leg on each foot block, each leg being notched at the upper end to matingly receive side supporting elements for said pier, and a plurality of deck boards supported by said side supporting elements, each joint of said pier being matingly assembled and keyed for substantially rigid but temporary easily demountable assembly.

8. A knock-down pier having permanently embedded spaced foot blocks each comprising a pile member having a flange rigidly fixed thereto below the top thereof, said pile member terminating below the low water surface and extending only a short distance above the water bottom level, a vertical leg post demountably on each foot block and supported thereby, each of said leg posts being notched at the upper end to matingly receive and demountably support side supporting channels and a plurality of deck boards demountably fastened to said side channel members.
